UNITED STATES PATENT OFFICE.

BURT M. LUTZE, OF FLINT, MICHIGAN, ASSIGNOR TO GENERAL MOTORS CORPORATION, OF DETROIT, MICHIGAN, A CORPORATION OF DELAWARE.

SPARK-PLUG-TERMINAL CONNECTION.

Application filed January 30, 1920. Serial No. 355,087.

To all whom it may concern:

Be it known that I, BURT M. LUTZE, a citizen of the United States, and a resident of Flint, county of Genesee, and State of Michigan, have invented certain new and useful Improvements in Spark-Plug-Terminal Connections, of which the following is a full, clear, concise, and exact description, such as will enable others skilled in the art 10 to which the invention relates to make and use the same, reference being made therein to the accompanying drawings, which form a part of this specification.

My invention relates to ignition systems 15 for use with internal combustion engines, and the object thereof is to provide an improved connection or joint by the use of which the leading in conductors or cables may be more readily attached to and detached from the spark plugs of the igniting system of the engine than has heretofore commonly been the case.

A further object of my invention is to 25 provide a joint or connection for use in ignition systems and in which the leading in electrical conductors or cables may be attached to and detached from the central electrode of the plug by imparting angular movement to the said conductors about the 30 central electrode of the plug as a pivot; and which connection when made and in use will be of such a character that it will not become accidentally broken or the supply conductor disengaged from the plug, due to the 35 vibration of the engine or to other causes.

With the above and other objects of invention in view, my invention consists in the improved terminal connection for use with spark plugs illustrated in the accompanying drawing and hereinafter described and claimed; and in such variations and modifications thereof, within the scope of the concluding claims, as will be obvious to those skilled in the art to which my invention relates.

Referring now to the drawing wherein the preferred embodiment of my invention is illustrated:

Figure 1 is a view showing an electric conductor attached to the central electrode of a spark plug by means of my improved connection or joint, the elements being shown in plan.

Figure 2 is a view showing the under side 55 of the terminal with which the leading in

conductor or cable is provided, for the purpose of conveniently attaching said cable to and detaching it from the plug, the view being upon a larger scale than Figure 1.

Figure 3 is a view showing a spark plug 60 and leading in conductor connected therewith through and by means of my improved terminal connection in side elevation.

Figure 4 is a view showing the elements 65 whereby the leading cable is connected with the plug partly in section, and upon a larger scale than in Figure 3, the view for the most part being upon a longitudinal plane indicated by the line 4, 4, Figure 2.

Referring now to the drawing, the reference numeral 5 designates the external shell 70 or casing of an ordinary type of spark plug, 6 the main insulating member thereof made ordinarily of porcelain and held in place within the shell 5, and 7 the central electrode 75 of the plug which extends through a passage provided in the insulator, all as is usual in spark plugs.

The upper end of the electrode 7 which is obviously the outer end thereof when the plug is in use is provided with a threaded portion 8; the threads being shown as provided upon the exterior surface of an upwardly extending portion or sleeve 9 of a nut 10 which is in threaded engagement with the upper end of the electrode, although it will be appreciated that the threaded portion or member at the upper end of the electrode may be provided otherwise than by the use of a nut which is separate and distinct 85 from the electrode.

The reference numeral 11 designates the leading in conductor or cable through which 90 electricity is supplied to the central electrode of the plug, such conductor being illustrated as in the form of a plurality of fine wires stranded together and the conductor as a whole being covered by heavy insulation, ordinarily of rubber, as indicated by the reference numeral 12.

The reference numeral 13 designates a terminal with which the stranded supply conductor 11 is connected, and which terminal in effect forms a continuation of the electrical conductor provided by the wires; said terminal being illustrated as made from a thin sheet metal blank having wings 14 turned over and made to grasp the sheath 15 of the wires 11, and having also projections 105 which in a finished terminal provide lugs 16 110

which embrace the nut 17 and hold the same in permanently fixed relation with the terminal and with the leading in conductor; so that the nut in effect forms an integral part 5 of the terminal and of the conductor through which current is supplied to the plug.

I wish to here state, however, that the particular manner in which the terminal, which forms a continuation of the wires 11 10 and is in effect a part of the leading in electrical conductor through which current is supplied to the plug is provided, is quite immaterial; and that said terminal is not necessarily made from a blank shaped in the manner hereinbefore explained, together with a nut as an element separate and distinct from the casing formed by the blank and which encloses a nut, as in the embodiment of my invention illustrated and herein described.

20 In the form of my invention shown the neck portion formed by turning over certain portions of the blank referred to to form the wings 14, extends into the exterior rubber insulation of the leading in conductor, 25 to thereby provide a more effective insulation of the end portion of the electrical supply conductor.

The end portion of the electrical conductor through which current is supplied to the 30 plug is provided with an opening, said opening being in the nut 17 of the terminal 13, which is in effect a part thereof, in the form of my invention illustrated. This opening is threaded to correspond with the threaded 35 end portion 8 of the central electrode; so that the end portion of the leading in conductor may be screwed onto the upper end of the said central electrode.

It will be appreciated that the terminal 40 above referred to forms in effect an integral or more strictly speaking a unitary portion of the leading in conductor, and that the terminal is in no way movable relative to or independently of the end portion of the said 45 conductor. It therefore follows that the leading in conductor may be connected with and disconnected from the central electrode by rotating said conductor terminal about an axis corresponding with the axis of the 50 central electrode, during which angular movement the threads within the opening of the terminal portion of the conductor and the threads at the upper end of the central electrode are made to engage with and disengage 55 from one another; the threads in the two members aforesaid thus forming co-operating locking elements which, when in engagement, act to detachably hold the end of the leading in conductor fixedly attached 60 to the central electrode.

The terminal of the leading in conductor and the wire or wires thereof being thus in permanent and fixed relation with one-another, because of the integral construction 65 of the parts, it follows that the parts of the

leading in conductor all move together in attaching the same to and detaching it from the central electrode, and, in order that the angular motion imparted to the conductor to effect this connection with and disconnection 70 from the plug may be reduced to as small an extent as possible, a multiple thread is preferably provided upon the threaded end portion of the electrode, the individual threads of which are arranged at a large angle relative to a horizontal plane extending through the electrode; the steepness of the threads being such, in the embodiment of my invention illustrated, that angular movement 75 throughout about 90 degrees will be sufficient to screw the terminal onto the threaded portion of the electrode and provide a connection between the two which will be secure and one which will not jar loose, due to the vibration of the engine, when the device is 80 in use. It will be appreciated, however, that the steepness of the threads, their number, and other details of the locking elements provided by the threads upon the electrode and within the opening of the terminal of 85 the leading in conductor, are matters of degree, and may be varied throughout wide limits without departing from my invention.

In ignition systems such as are commonly used in internal combustion engines the 90 leading in conductors through which current is supplied in proper sequence to the plugs of the various cylinders lead from a suitable distributor, and are of considerable length, so that there is quite a little slack 95 in the said conductors; the slack being sufficient to permit the individual conductors to be rotated throughout angles sufficient to accomplish their connection with and disconnection from the plugs without disturbing the connections of their other ends 100 with the distributor. My improved connection or joint therefore provides for connecting the ends of the leading in conductors with the plugs by swinging the conductor terminals about the central electrodes of the 105 plugs as pivots, thereby providing an ignition system in which the said conductors may be readily disconnected from the plugs by swinging their terminals about the plugs, 110 and as readily reconnected with the plugs by a similar process; in each case without disturbing the fixed connections between the other ends of the supply conductors and the distributor. The threads upon the central electrode and within the opening in the terminal of the leading in conductor are ordinarily so related as to provide a comparatively loose joint between the parts to thereby facilitate the attachment of the cables 115 to the plugs without binding. Such looseness as may be present, however, will in no way interfere with the passage of the high tension current employed to the central electrode; and the vibration of the engine will 120 125 130

tend to cause the terminals of the leading conductors to move downward which movement will tighten the joint between the terminal and the threaded portion of the central electrode, thus providing a connection which tends to become tighter when in use, and one which will not jar loose nor become disconnected due to the vibration of the engine.

5 10 Having thus described and explained my invention I claim and desire to secure by Letters Patent:

1. In a device of the class described, an internally threaded nut adapted to be attached to the central electrode of a spark plug, said nut provided with an external thread of coarse pitch, a terminal for a conductor provided with an internal thread for engaging the external thread of said nut, 15 substantially as shown and described.

2. In combination, a spark plug having a central electrode provided with a coarsely threaded portion at its outer end; a terminal having an opening which is internally threaded to correspond with the threaded end portion of said electrode; and an electrical conductor secured to said terminal, the end of said conductor and all elements comprising said terminal being fixed relative to one another.
